DESIGN FOR A MILLING MACHINE SADDLE

Joseph B. Armitage, Wauwatosa, Wis., assignor
to Kearney & Trecker Corporation, West Allis,
Wis., a corporation of Wisconsin

Application September 9, 1937, Serial No. 71,523

Term of patent 14 years

To all whom it may concern:

Be it known that I, Joseph B. Armitage, a citizen of the United States and resident of Wauwatosa, in the county of Milwaukee and State of Wisconsin, have invented a new, original, and ornamental Design for a Milling Machine Saddle, of which the following is a specification, reference being had to the accompanying drawing, forming part thereof.

Figure 1 is a view in perspective of a milling machine saddle, showing my new design;

Figure 2 is a view in front elevation of the milling machine saddle shown in Figure 1;

Figure 3 is a view in top elevation of the same saddle, and

Figure 4 is a view in bottom elevation thereof.

I claim:

The ornamental design for a milling machine saddle, substantially as shown.

JOSEPH B. ARMITAGE.
